Primary Examiner — Kathleen L Jones(74) *Attorney, Agent, or Firm* — J.C. Patents(57) **CLAIM**

The ornamental design for a supercomputing device, as shown and described.

DESCRIPTION

FIG. 1 is a front view of a supercomputing device;
 FIG. 2 is a rear view of the supercomputing device;
 FIG. 3 is a left view of the supercomputing device;
 FIG. 4 is a right view of the supercomputing device;
 FIG. 5 is a top view of the supercomputing device;
 FIG. 6 is a bottom view of the supercomputing device;
 FIG. 7 is a perspective view of the supercomputing device;
 FIGS. 8 to 16 are detail views of the encircled portions on FIG. 1;
 FIGS. 17 to 28 are detail views of the encircled portions on FIG. 2;
 FIGS. 29 to 34 are detail views of the encircled portions on FIG. 3;
 FIGS. 35 to 46 are detail views of the encircled portions on FIG. 4;
 FIGS. 47 to 71 are detail views of the encircled portions on FIG. 5;
 FIGS. 72 to 82 are detail views of the encircled portions on FIG. 6; and,
 FIGS. 83 to 97 are detail views of the encircled portions on FIG. 7.

The evenly spaced broken lines depicting portions of the supercomputing device form no part of the claimed design. The line-dot-line broken lines that encircle portions of FIGS. 1-7 and that border the FIGS. 8-97 detail views indicate outer limits of enlarged areas of the figures and form no part of the claimed design.
